SWIM FIN

Thomas A. Chesney, 2050 Laura Ave.,
Huntington Park, Calif. 90255

Filed Nov. 14, 1969, Ser. No. 20,097

Term of patent 14 years

Int. Cl. D21—03

U.S. Cl. D71—1

Fig. 4.Fig. 5.Fig. 6.Fig. 7.FIG. 1 is a top plan view of a swim fin embodying my new design;

FIG. 2 is a bottom plan view;

FIG. 3 is a side elevational view, both sides being identical;

FIG. 4 is an end view taken from the free end;

FIG. 5 is an end view taken from the end which is attached to the foot;

FIG. 6 is a longitudinal sectional view taken on line 6-6 of FIG. 1;

FIG. 7 is a transverse sectional view taken on line 7-7 of FIG. 1.

I claim:

The ornamental design for a swim fin, substantially as shown and described.
